UNITED STATES PATENT OFFICE

HARRY S. BURNHAM, OF SCHENECTADY, NEW YORK

LOCOMOTIVE CROSSHEAD

Application filed May 12, 1927. Serial No. 190,788.

My invention relates to cross heads, operating in steam engines, in connection with fixed guides, to ensure and maintain the normal reciprocating movements of their pistons, and more particularly relates to those applied in locomotives of the three cylinder type, on the piston rod of the middle cylinder thereof. The object of my invention is to provide a crosshead of such improved construction as will facilitate its maintenance in service, and effect a saving of time and labor in taking up wear, when it becomes necessary or desirable to do so.

The improvement claimed is hereinafter fully set forth.

In the accompanying drawing: Figure 1 is a side view, in elevation, of the forward portion of a three cylinder locomotive embodying my invention, a portion being broken away, to illustrate more clearly the relation of the cross head to the middle cylinder; Fig. 2, a similar view, on an enlarged scale, of the cross head and a portion of its guide; and Fig. 3, a vertical transverse section, on the line *a a*, of Fig. 2.

The cross head guides which are herein set forth are of the type generally applied in connection with the middle cylinder of a three cylinder locomotive, by reason of their presentation of a comparatively large area of bearing surface to oppose the upward thrust of the forward end of the main connecting rod, and also because of the absence of interference between the front axle and a lower guide bar, which would exist with the application of a cross head of the alligator type. Prolonged service naturally results in wear of the sliding surface of the shoe of the cross head, and when the shoe is formed integrally with the body of the crosshead it is necessary, preliminarily, that the locomotive be spotted in such position as will enable the wrist pin to be backed out, as it is accessible only between the spokes of the front driving wheels. Further, the cross head must be disconnected from the piston rod, by driving out the tapped key by which it is connected thereto. These operations require time, and it is difficult to perform the work in the narrow

confines of the space which is available. Moreover, it is obviously desirable to avoid, if possible, the severance of a connection as important as that of the cross head and the piston rod.

In the practice of my invention, referring descriptively to the specific embodiment thereof which is herein exemplified, the cross head, which is of the Dean type, comprises two detachable sections; a body, 1, provided with bores, in which the wrist pin, 2, is fitted in the ordinary manner, and a shoe, 1a, comprising a tongue, interfitting between the spaced cheeks 1c of the body portion, and a head having a top bearing face for engaging the bottom face of a top guide bar, 6, and extensions, 1b, at each side, overlying and bearing on lower laterally spaced guide bars, 6a, of L section. The shoe is detachably secured to the body, by transverse bolts, 3, and nuts, 3a. The bolts pass through the cheeks of the body and the tongue of the shoe. The body of the cross head is connected to the piston rod, 4, by a key 5.

To provide for preventing the cheeks, 1a, of the body 1, both from spreading and closing in, they are each provided with an extension 1d, below the wrist pin 2, formed with a bore for the passage of a bolt 1e, which bolt carries a spacing sleeve 1f, that is interposed between the cheeks. A nut 1g, on the bolt serves to hold the cheeks against spreading, and the sleeve 1f, serves to prevent their closing in.

The lower guide bars, 6a, are detachably fastened to the top guide bar, by vertical bolts, 6b, and nuts, C.

It will be seen that the location of the bolts, 3, by which the shoe is connected to the body of the cross head, is such that they are readily removable below the guide bars, and when it becomes necessary to take up wear on the sliding surfaces of the cross head, the shoe is removed, relined, and replaced, or a new shoe, having lined surfaces of full thickness, is applied without disturbance of the body of the cross head, the main connecting rod, or the piston rod. The resultant economy of time and labor will be obvious.

I claim as my invention and desire to secure by Letters Patent.

1. In a crosshead and guide for engines, the combination of a guide having an upper bearing face and laterally disposed lower bearing faces, providing a pair of oppositely disposed grooves; a shoe having lateral extensions fitted in the grooves and a depending tongue intermediate the grooves; a body 5 detachably connected to, entirely supported by, and depending below said tongue and comprising spaced cheeks each formed with a wrist pin bore, extensions below the wrist pin bore, and transverse detachable means connecting the extensions; and means for detachably fastening the body to the tongue.

2. In a crosshead and guide for an intermediate piston of locomotives having at least three cylinders in transverse series, the combination of a guide comprising an upper rail, two transversely spaced lower rails, and means for detachably fastening the lower rails to the top rail, said rails providing oppositely disposed grooves; a shoe having a 10 pair of lateral bearing members, each fitted in one of the grooves, and a pair of transversely spaced, longitudinal tongues depending between and below the lower rails; a body entirely supported by the tongues and 15 comprising a pocket adapted to receive the tongues, means for connection to a piston rod and means for connection to a driving rod; and bolts passing through the body and the tongues, detachably connecting such parts 20 together.

3. In a crosshead and guide for an intermediate piston of locomotives having at least three cylinders in transverse series, the combination of a guide comprising an upper rail, two transversely spaced lower rails, and means for detachably fastening the lower rails to the top rail, said rails providing oppositely disposed grooves; a shoe having a 25 pair of lateral bearing members, each fitted in one of the grooves, and a longitudinal tongue depending between and below the lower rails; a body entirely supported by the tongue and comprising a pocket adapted to receive the tongue, means for connection to the piston rod, and means for connection to a driving rod; and bolts passing through the body and the tongue, detachably connecting such parts 30 together.

4. In a crosshead and guide for an intermediate piston of locomotives having at least three cylinders in transverse series, the combination of a guide comprising an upper rail, two transversely spaced lower rails, and means for detachably fastening the lower 35 rails to the top rail, said rails providing oppositely disposed grooves; a shoe having a pair of lateral bearing members, each fitted in one of the grooves, and a longitudinal tongue depending between and below the lower rails; a body entirely supported by the 40

tongue and comprising spaced cheeks each having a wrist pin bore, an extension below the bore, detachable transverse means connecting the extensions and holding the same from spreading and closing in, and means for connection to a piston rod; and bolts passing through the walls of the pocket, and the tongue, detachably connecting the body to the shoe.
